FRAMED STRING DECORATION

Neil J. White, Los Angeles, Calif.
(929 W. Spruce St., Inglewood, Calif.)

Filed Dec. 29, 1959, Ser. No. 58,840

Term of patent 14 years

(Cl. D29—23)

The back is plain and unornamented.

I claim:

The ornamental design for a framed string decoration, substantially as shown and described.
